UNITED STATES PATENT OFFICE.

GEORGE H. STEARNS, OF ROXBURY, MASSACHUSETTS.

ROTARY ENGINE.

1,378,430.

Specification of Letters Patent. Patented May 17, 1921.

Application filed June 11, 1918, Serial No. 239,462. Renewed October 14, 1920. Serial No. 417,017.

To all whom it may concern:

Be it known that I, GEORGE H. STEARNS, a citizen of the United States, residing at Roxbury, in the county of Suffolk and State of 5 Massachusetts, have invented certain new and useful Improvements in Rotary Engines, of which the following is a specification.

This invention relates to improvements in 10 rotary internal combustion engines. More particularly it relates to engines, adapted to work with gasolene or the like fuel, provided with a rotating member mounted eccentrically within an approximately circular 15 chamber and having a piston which sweeps around the wall of the chamber as the said member rotates, sliding through said member during each revolution as its eccentricity requires. Engines of this type have been 20 proposed many times heretofore, on account of the manifest advantages of simplicity of construction and operation, few wearing parts, and compactness and speed; but so far as I am aware, none have been equal to 25 the device which I am about to disclose or have proven successful. The present invention comprises improvements in a number 30 of respects. One feature deals with the packing of the piston blade, so that it is tight against leakage of gases, and automatically flexible, taking up its own wear. Another feature relates to the reduction of 35 friction between the piston and the chamber wall; and another feature relates to the provision of a balanced rotary engine, a simple method of cooling it, and the making 40 of simple passages and controls therefor for inlet of air and fuel, for exhaust of products of combustion, and for compression of the air and fuel as an intermediate stage during 45 operation. The invention contains other novel features of advantage as will appear from the description which follows. It may be embodied in various forms within the scope of the appended claims. It is intended 50 that the patent shall cover by suitable expression in the appended claims whatever features of patentable novelty exist in the invention described.

50 The objects of the invention as regards packing of the piston blade are accomplished by providing said blades with a flexible edge which presses and rubs constantly against the walls of the chamber. The balanced 55 construction is provided, when desired, by

making two of the chambers with their rotating members 180° apart. These may be on the same main shaft or may be on parallel shafts geared together. A single intake may serve them both; and a single exhaust. 60 Also a single chamber intervening between them may receive the compression from and may discharge the mixture into each for combustion. The ports of this compression chamber and the inlet and exhaust ports, for 65 one part of the engine, may all be controlled by a single valve disk. A similar disk may serve the other part likewise. Thus these two parts in one sense constitute separate engines, for the engine can be made with 70 only one of these chambers with its rotating piston and incidental valves and compression chamber; but if the two be used, they coöperate effectively as parts of a single engine. The engine is so arranged that the 75 rotating parts are kept cool by internal centrifugal action on water, by virtue of their own rotation without requiring a separate pump. Details by which these ideas are carried out are illustrated in the accompanying 80 drawings, in which,

Figure 1 is an end elevation, in section on a plane crossing the main shaft or shafts perpendicularly in the middle of the explosion chamber;

85

Fig. 2 is a side elevation of a detail in section on the line 2—2 of Fig. 1, somewhat diagrammatically indicating the water circulation and cooling system;

Fig. 2^a is a side elevation of a modification of this feature, on a smaller scale;

Fig. 3 is a plan of the engine shown in Fig. 1, with one of the chambers and its surrounding parts in section on the line 3—3 of Fig. 1;

95

Fig. 4 is a view looking in the same direction as Fig. 2 and indicates details of the valve disk;

Fig. 5 shows details of the piston flexible edge packing;

100

Fig. 6 is a plan of a modification in which the two rotating power members are on the same shaft;

Fig. 7 is an end elevation of the same with part broken away to show the valve arrangements.

Fig. 8 is a plan of a further modification.

Referring to the drawings, Fig. 1 shows an arrangement in which there are two rotating members 10 each within a chamber 11 110

and having a piston blade 12 which penetrates the rotating member diametrically and is capable of moving through it reciprocatingly in the direction of its length. 5 The chambers 11 and rotors 10 are approximately circular when viewed in the direction of Fig. 1, and have a rounded periphery when seen as cut by a plane passing through the axis of rotor or chamber, as in Fig. 2 or 10 Fig. 3. Each piston blade has, at its end, rollers 13 adapted to reduce the friction with which the end of its main portion rubs on the internal periphery of the chamber, whenever such rubbing occurs, and has flexible 15 laminated edges consisting of sheets of metal 14 which project from it to the end, and to the sides of the chamber on each side of the main body part of the piston. These prevent leakage of gas past the piston blade. 20 The action is that as the member 10 rotates the piston 12 which passes through it sweeps around the chamber. Part 10, being circular and being eccentric within the chamber 11, is so placed that its convex periphery practically 25 makes tangential contact with the concave periphery of the chamber at a fixed point which, in Fig. 1, is at the place where the two chambers are nearest together, as would be seen if it did not happen that 30 in that figure the piston is portrayed as occupying the position stated. When the piston has swept on in the direction of the arrow from the place in which it is portrayed, the round wall of the rotating member 10 makes tangential contact as above 35 stated with the interior surface of the chamber at the point where these two would be cut by the axis of the adjacent valve disk 15. As the total length of the piston in the 40 position illustrated in Fig. 1, where its axis coincides with a diameter of chamber 11, is greater than the length which it could have when its axis coincides with the line 2—2 of that figure, which is only a chord of the chamber 11, if that chamber were strictly 45 circular, it is preferable to make that chamber not strictly circular but to flatten it a little in the direction in which the piston extends in Fig. 1, and to design it on a 50 graduated scale so that the piston will fit all of the way during its sweep around the chamber, according to principles already known; but if preferred, and this is one of the advantages of the invention, the chamber 55 11 may have a strictly circular periphery which is considerably cheaper to make; and the variation in length between the chord on the line 2—2 and the diameter on the line beginning at 3 may be compensated by periodic 60 yielding of the flexible edges of the piston. Said flexible edges constitute the packing and consist of blades of flexible metal on each side of the piston, secured there by blocks 16, which compress the central portions thereof upon the piston. They 65

project laterally from the main body of the piston to the walls of the chamber and as illustrated in Fig. 1 are at their tips bowed outward from the piston. Being flexible and being divided into as many segments as desired, they can bend in and out; and as wear occurs, can extend farther, so as to be always in contact with the wall of the chamber. They are illustrated as if the packing on each side of the piston were 70 made of a series of layers of flexible metallic plates, whose thickness is necessarily somewhat exaggerated in the drawing, each layer being in two parts, one of which extends around one end and one side of the piston 75 blade, the remaining end and side being covered by another blade set in the same plane. As the exigencies of curvature of the peripheral wall or of the side walls of the chamber require, they may be subdivided, by slits extending inward from their edges, into as many and as small units in each plane as is desirable, in order to get sufficient flexibility and closeness of fit to the wall while yieldingly pressed against it, 80 notwithstanding the curvature of the surface against which they press. And in that case the successive laminae may be arranged to lap the cracks between adjacent leaves in the same plane. They may be secured to the piston by fastenings in the nature of bolts 17 but it is to be observed that as the parts rotate rapidly they tend always to be held out by centrifugal force against the periphery of the chamber; and they 85 might be secured only loosely in the central portion. The slot 18 indicates how provision may be made for their adjustment when set, or for their automatic throw-out centrifugally to keep themselves tight. 90 When each layer consists of at least two separable pieces as illustrated, these are free to fly apart, each seeking the periphery of the chamber next to its own eccentric portion which is unbalanced. Whether thus 95 automatically moved outward, or whether otherwise set, they press against the periphery and sweep along upon it at an angle which is obtuse, when viewed from the chamber gas side, so that any high pressure of gases in the chamber tends to press the laminated edges of the packing more 100 tightly against the chamber wall. Any lubricating oil which may be on that wall is scraped or plowed, as it were, from the 105 wall by the advancing edge of the blade, but the oil thus gathered on that advancing edge, instead of being thrown inward as it would be if the motion were rectilinear, is kept thrown back to the edge of the packing 110 by centrifugal force, and hence is kept directly at the rubbing edge. By this rubbing, also, all deposits of carbon are kept 115 clear from the surface of the chamber. 120 125

A compression chamber 20 is provided, 130

which in Fig. 1 is arranged midway between the two working chambers 11. Each chamber has ports 21 for intake and 22 for outgo. The valve disk 15 has openings 5 which communicate with these ports at different distances from the axis of the valve disk so that the port 21 is alternately connected with the compression chamber 20 and with the intake of air and gas 19, while 10 the discharge port 22 is alternately connected with the compression chamber 20 and with the exhaust passage 23. A spark plug or other suitable ignition device may be inserted as at 24; and gearing, for connecting the valve disk 15 with the main shaft 25 on which the rotating members 10 are carried, may be provided as indicated 15 at 26 and 27. The chamber 11 may be made in halves held together by bolts 28 and separable on their medial planes as indicated 20 in Fig. 3. As thus constructed, and with such supplementary details as are needed for lubrication and other incidentals according to principles of machine design 25 that are well known, the apparatus operates with intake in one side,—for example, the bottom part as represented in Fig. 1 of the chamber 11 at the left,—while the exhaust is proceeding in the upper part of 30 the same, followed by the introduction to the said lower portion of some of the accumulated compressed charge contained in chamber 20, and by ignition thereof. The gas that was formerly in said part of the 35 chamber is then in the upper part, at first undergoing compression therein and then simultaneously therewith, *i. e.* while compression continues passing into the compression chamber 20. After this, intake 40 again occurs in the lower part and that which had been burning in the lower part is expelled from the upper part into the exhaust passage 23. A similar cycle occurs in the other chamber 11; and the stresses 45 are substantially balanced.

The piston cooling is indicated in Fig. 2. Water entering at the axis at the right of that figure flows into the hollow center 30 of the shaft 25, and flows out through 50 peripheral openings 31 in the other end of the same shaft into a groove 32 (Fig. 3) whence it flows by holes 33 into the water space 34 in the wall of the chamber 11. Entering at one end of this it finds its escape at the other end through a pipe 35. It is propelled through this course by the 55 rotary movement given to it in the interior of shaft 25; its escape holes 33 therefrom being on a larger circle than its entrance so that centrifugal force throws it out, at the holes 31. In passing from one end of shaft 25 to the other it is compelled by a fin 30' to go out around the inside of the periphery of the main rotating member 10; 60 and as the water enters this member close

to the place where the piston slides through it, and leaves it close to the same, the arrangement provides for cooling all of the important regions by water in close proximity. The fin 30' might be made helical, as 70 an element of a screw, as indicated at 30 in Fig. 2^a, and this would have some effect in starting flow of water quickly at the beginning of operations when the water is stationary. The arrangement as a whole 75 dispenses with need for an external pump.

The apparatus thus described has very few moving parts, and therefore should be simple in construction, sturdy in operation; and as it automatically keeps the piston 80 tight and fresh packing is easily installed, it should last well under service conditions.

It has rollers 13 at the ends of the main body of the piston, between the flexible edge laminae, which relieve the laminae in case 85 so great a stress is imposed upon them that they bend enough to let the rollers make contact; and in that case the rollers prevent an increase of friction due to hard rubbing of the ends of the laminae. The relations 90 of the cycle sequences in the two chambers to each other can be varied by variations in the setting or in the design of the valve disks, and if necessary in the gearing connections. By due attention to such simple 95 matters of design the rotors may, for example, be made to work in unison, in an angular sense, or 180° apart; in the same direction or opposite; with explosions in the under part of each chamber or with one under 100 and the other upper.

In this way various kinds of balance are obtainable, with explosions simultaneously or alternating.

If for example the explosions be alternating and both in the lower parts, the compressive discharges into the compression chamber will be alternating from the two upper parts; and will make practically a continuous stream of compressed inflow. 105 The idea of maintaining a reservoir of compressed mixture of uniform pressure may be approached more closely by a development of the arrangement indicated in Figs. 6, 7, and 8. Figs. 6 and 7 show two rotors 110 on the same shaft, which may be preferred in some cases. By the arrangement indicated in Fig. 8 a more compact engine is produced in which the passage that constitutes the compression chamber is shorter, 115 and hence conducive to higher compression. It also has the characteristic that an indefinite number of chambers can be arranged on the same shaft, with their compressed charges all delivered into a single 120 compression chamber, which in consequence may have practically a uniform pressure, and with their explosions occurring all around the circle of revolution of the shaft, 125 or at such regular and rapid succession and 130

at such angular positions as may be desired, giving either balance, or continuous torque, or both.

In all of the modifications illustrated, there is a possibility of leakage from the part of the chamber in which the expansion occurs, and this is prevented in the main by the above described packing of the rotating piston; but there are times during each revolution when the approach of the solid body of the rotary member to the chamber wall is a part of the inclosure. When the engine is new, this can be made so as to fit closely against the wall of the chamber with a contact that is practically tangential at a place mid-way between the ports of the chamber; but with wear, leakage might develop along this line of contact. The drawing therefore illustrates a device which may be used for making of the chamber tight in such an exigency, and which has the further benefit that it permits of the engine being manufactured initially without the expense incidental to the great care required for making this contact tight. This device consists in the provision of a recess 40 in the adjacent wall of the chamber, and the setting thereon of a packing 41, somewhat resembling that of the pistons, comprising a plate or series of plates in the form of laminæ which spring inward elastically against the rotating member and whose terminal edges are shaped in conformity to the periphery of the rotating member and, pointing in its general direction of rotation, bear thereon at their very tips. These are tight against the sides of the recess 40, and may be bent against them upon the same principle that the flexible edge plates of the piston are bent, and are at their bases secured by bolts and soft packing, if necessary, so that no gas can pass around their bases. As they point toward the portion of the chamber where the explosion occurs, the pressure of such an explosion forces gas upon the backs of these plates, and so presses them the more firmly against the rotating member and thus prevents the escape of gas. As a compression period of the cycle is occurring beyond this packing while the combustion goes on, the difference of pressure is less than it might be. During the period of intake, which follows the combustion in the same part of the chamber, the other part of the chamber is open to the exhaust passage, and hence has not sufficient pressure to force contents past this stationary packing to any material extent; and such tendency of that sort as exists may be counteracted by the stiffness with which spring laminæ 41 bear on the rotating member. It will be observed that the piston packing laminæ 41 rub past these laminæ 41 twice at each half revolution; but the angles of setting of both are such that the piston laminæ wipe the fixed

packing lamine from the rear forward and hence can pass smoothly.

In the arrangement of the invention illustrated in Figs. 1 and 4 of the drawing, the valve disks 15 are designed for the several periods of the cycle to occur in pairs in each chamber. The valve shown in Fig. 4 has ports at four different distances from the axis. Of these, those marked 42 and 43 which are nearest to the axis 44 of the disk register with the port 22, the opening 42 connecting that port with the compression chamber 20, and the opening 43 connecting it with the exhaust passage 23. As these are located in different sectors of the circumference, being thus by their angular setting timed so that neither is opened when the other is open, there is no possibility for contents of the compression chamber 20 to escape by blowing through port 22 through the openings 42, 22, and 43 to 23 as it might if they were open at the same time. Similarly the openings 45 and 46 which register with the port 21 are in different sectors, the former of these registering with the compression chamber 20 and the latter with the inlet passage 19 at separate times. In operation, a mixture is drawn in to one side of the piston from 19 through 46 and 21 and then immediately when the piston has swept past the port 21 the mixture is drawn through the same passages to the other side of the piston until the end of the opening 46 is reached which is after substantially a complete revolution of the rotary piston-carrying member. After the leading end of the piston has again passed the port 21, the passage from the compression chamber 20 is open through 45 for a brief period and then is closed, and is opened again when the other end of the piston has passed the port 21, until the necessary charge has been introduced. Following the course of the mixture first mentioned as being drawn in behind the leading edge of the piston through passages 19, 46 and 21, this undergoes compression after the rear end of the piston has passed the port 21; and when the leading end of the piston has passed port 22 it is discharged into the compression chamber 20 through the port 22 and the opening 42. The charge immediately following, which was taken in through port 21 behind the rear end of the piston reaches the port 22 immediately behind it and is likewise forced into the compression chamber through the same opening 42. After the ignition and expansion of the first charge, which passes through compression chamber 20 through opening 45 and port 21 into the chamber 11 behind the leading end of the piston, the products of combustion go out through the passage 22, opening 43 and exhaust passage 23 and are followed immediately by the similarly expanded products which are behind the following

end of the piston through the same opening 43. This provides two explosions in succession in the chamber at the left of Fig. 1, during one revolution of the piston, and 5 none during the next. Meanwhile, in the chamber at the right in Fig. 1, the same occurs but with the two explosions happening during the time when no explosions occur in the chamber at the left. The advantage of 10 this arrangement is that it permits of a valve disk 15 rotating at half the speed of the pistons without leakage through conjunction of valve openings. If, however, the valve were made to rotate at the same 15 speed as the rotating piston member, the periods of the cycle might follow each other in a single succession in each piston chamber, the device of arranging them in pairs being primarily for the purpose of making 20 possible the use of a half time valve with single inlet port 21 or single outlet port 22, each respectively serving its purpose, viz: intake and compression inlet at the port 21 and compression outlet and exhaust at the 25 port 22.

I claim as my invention:

1. In a rotary engine the combination, with the chamber and a rotary member mounted eccentrically within it, of a piston 30 adapted to slide through the rotary member on a diameter thereof and having flexible edges pressing obliquely against the walls of the chamber.

2. In a rotary engine the combination, 35 with the chamber and a rotary member mounted eccentrically within it, of a piston adapted to slide through the rotary member on a diameter thereof and having flexible edges pressing obliquely against the walls of 40 the chamber, laminated in multiple layers of thin material, whereby their rubbing edges spread apart somewhat.

3. In a rotary engine the combination, 45 with the chamber and a rotary member mounted eccentrically within it, of a piston adapted to slide through the rotary member on a diameter thereof and having flexible edges pressing obliquely against the walls of 50 the chamber, laminated in multiple layers of thin material, whereby their rubbing edges spread apart somewhat; the layers being 55 held loosely on the piston, and divided into segments, one for each end of the piston, whereby each may be kept out against the chamber periphery by centrifugal force.

4. In a rotary engine the combination, 60 with the chamber and a rotary member mounted eccentrically within it, of a piston adapted to slide through the rotary member on a diameter thereof and having flexible edges pressing obliquely against the walls of 65 the chamber, laminated in multiple layers of thin material, whereby their rubbing edges spread apart somewhat; and a block on the piston, holding said sheets centrally in par-

allelism with the main body of the piston while their edge portions are free to bend out from the piston.

5. In a rotary engine the combination, 70 with the chamber and a rotary member mounted eccentrically within it, of a piston adapted to slide through the rotary member on a diameter thereof and having flexible edges pressing obliquely against the walls of 75 the chamber, laminated in multiple layers of thin material, whereby their rubbing edges spread apart somewhat; the layers being severally slitted inward from their peripheries, and arranged with the slits overlapped by solid parts of other layers.

6. In a rotary engine the combination, 80 with a chamber and a rotary member mounted within it, of a piston adapted to slide through the rotary member, and cooling means for the rotary member and piston, 85 comprising the provision of a hollow in the member and its supporting shaft; means to introduce water thereto at the axis of the shaft, at one end; and means for escape of water therefrom at the periphery of the 90 shaft on the other side of the said member.

7. In a rotary engine the combination, 95 with a chamber and a rotary member mounted within it, of a piston adapted to slide through the rotary member, and cooling means for the rotary member and piston, comprising the provision of a hollow in the member and its supporting shaft; means to introduce water thereto at the axis of the shaft, at one end; and means for escape of 100 water therefrom at the periphery of the shaft on the other side of the said member; there being a hollow provided in the wall of said chamber; and communication to it from said escape means, for water that has passed 105 through the shaft; and means for escape of water from the chamber wall.

8. In a rotary engine the combination, 110 with a chamber and a rotary member mounted within it, of a piston adapted to slide through the rotary member, and cooling means for the rotary member and piston, 115 comprising the provision of a hollow in the member and its supporting shaft; means to introduce water thereto at the axis of the shaft, at one end; and means for escape of water therefrom at the periphery of the shaft on the other side of the said member; there being a fin in the hollow in the said member from the center outward, with water 120 passage at its periphery.

9. In a rotary engine the combination, 125 with a chamber and a rotary member mounted within it, of a piston adapted to slide through the rotary member, and cooling means for the rotary member and piston, comprising the provision of a hollow in the member and its supporting shaft; means to introduce water thereto at the axis of the shaft, at one end; and means for escape of 130

- water therefrom at the periphery of the shaft on the other side of the said member; there being a fin in the hollow in the said member from the center outward, with water passage at its periphery; said fin being an element of a screw, whereby water is propelled through said hollow.
10. In a rotary internal combustion engine the combination, with a chamber having inlet and outlet ports on one side, and a rotary member mounted eccentrically within it; of a piston adapted to slide through the rotary member on a diameter thereof as it rotates; a compression chamber; a rotary valve comprising a plate adapted to rotate past said ports and having openings adapted to register with them, and so to connect them with said compression chamber, and with supply and exhaust 20 passages.
11. In a rotary internal combustion engine the combination, with a chamber having inlet and outlet ports on one side, and a rotary member mounted eccentrically within it; of a piston adapted to slide through the rotary member on a diameter thereof as it rotates; a compression chamber; a rotary valve comprising a plate adapted to rotate past said ports and having openings adapted to register with them, and so to connect them with said compression chamber, and with supply and exhaust 30 passages; said rotary plate being a plane disk, and having its openings at diverse radial distances from its axis.
12. In a rotary engine the combination, with the chamber and a rotary member mounted eccentrically within it, of a piston adapted to slide through the rotary member on a diameter thereof and having flexible edges pressing obliquely against the walls of the chamber; the body portion of the piston having terminal rollers whereby the deflection of the flexible edges is limited.
45. 13. In a rotary engine the combination, with the chamber and a rotary member mounted eccentrically within it, of a piston adapted to slide through the rotary member on a diameter thereof and having flexible edges pressing obliquely against the walls of the chamber, laminated in multiple layers of thin material, whereby their rubbing
- edges spread apart somewhat; the said laminæ projecting far enough to constitute the normal endwise support for the piston, whereby the piston is of variable length.
14. In a rotary internal combustion engine the combination with a compression chamber of two piston chambers, pistons therein, and connections and valves whereby each piston chamber compresses into and draws its charge from said single compression chamber.
15. In a rotary internal combustion engine the combination with a compression chamber, of a plurality of piston chambers; pistons therein, all on the same shaft; and connections and valves whereby each piston chamber compresses into and draws its charge from said single compression chamber; said valves being rotary plates with openings, intervening between said piston chambers and compression chamber.
16. In a rotary engine the combination, with a chamber having inlet and outlet ports near together on one side and a rotary member mounted eccentrically within it, of a piston adapted to slide through the rotary member on a diameter thereof, and a spring plate arranged fixedly on the chamber wall and pressing upon the rotary member between said ports at a small angle to the tangential direction, pointing in the direction of rotation and constituting packing between the chamber wall and the rotating member.
17. In a rotary engine the combination, with a chamber having inlet and outlet ports near together on one side and a rotary member mounted eccentrically within it, of a piston adapted to slide through the rotary member on a diameter thereof, and a spring plate arranged fixedly on the chamber wall and pressing upon the rotary member between said ports at a small angle to the tangential direction, pointing in the direction of rotation and constituting packing between the chamber wall and the rotating member; the said plate comprising a series of laminæ whose extreme tip edges fit against the rotating member.

Signed at Boston, Mass., this 1st day of June, 1918.

GEORGE H. STEARNS.
